UNITED STATES PATENT OFFICE.

WILLIAM H. MARTIN, OF NEW YORK, N. Y., ASSIGNOR TO AMERICAN TELEPHONE AND TELEGRAPH COMPANY, A CORPORATION OF NEW YORK.

MEANS FOR NEUTRALIZING INTERFERENCE.

1,329,842.

Specification of Letters Patent.

Patented Feb. 3, 1920.

Application filed February 28, 1919. Serial No. 279,728.

To all whom it may concern:

Be it known that I, WILLIAM H. MARTIN, residing at New York, in the county of Bronx and State of New York, have invented certain Improvements in Means for Neutralizing Interference, of which the following is a specification.

This invention relates to signaling systems, particularly to arrangements for the reduction of interference due to disturbing influences affecting the transmission line. Its object is to provide a simple and efficient arrangement for the reduction or elimination of interference, especially where a number of lines are subject to the same disturbing influences.

The invention finds a most useful field in submarine cable terminals, but it is applicable also to land lines, and to complete metallic circuits as well as to grounded lines.

Figure 1 illustrates diagrammatically the invention applied to the reduction of interference in a plurality of cable terminals. Fig. 2 shows a modification. Fig. 3 shows another modification using no inductive connections, and Fig. 4 shows the modification of Fig. 3 applied to a set of duplexed lines.

Referring to Fig. 1, 5 and 6 represent two cables or other lines which are exposed to similar disturbing influences, such, for instance, as the inductive action of adjacent power circuits or of atmospheric disturbances. These lines are illustrated as terminating in the usual duplex sets comprising the sending circuits 7 and 8, and receiving circuits 9 and 10, respectively, the receiving apparatus R in each case being connected to the line through a transformer,—11 and 12 respectively. 13 is a conductor subject to the same disturbing influences as affects the lines 5 and 6. It may be a complete line paralleling the lines 5 and 6, in which case it may, when properly balanced, be used for transmitting signals by the employing of the usual duplex arrangement provided with a sending branch 14. It may, however, be a small gage conductor passing only through the zone of interference, and if used with cables it extends to a sea ground a sufficient distance out to intercept most of the disturbance affecting the cables to be protected. It may be grounded through an artificial line located at the grounding point, designed with the conductor itself to simulate electrically the lines 5 and 6.

A transformer 15 has its primary in the conductor 13 for the purpose of receiving the potentials created by the disturbing influences. Where 13 is a circuit used for sending this transformer is located in the receiving branch of the duplex set as shown. Transformers 11, 12 and 15 should be designed to produce similar distortion of the interference, and the impedances connected to the secondaries of these transformers should be arranged to permit the interference voltages produced in the secondaries of the transformers to be of the same wave shape and phase. Across the output of the transformer 15 are connected impedances 16 and 17, and across each impedance is connected a vacuum tube amplifier,—18 and 19 respectively. The amplifiers may have one or more stages, as the requirements of the circuit dictate. The output circuit of the amplifier 18 is connected across the terminals of impedance 20 in the receiving circuit 9 of line 5, and the output circuit of the amplifier 19 is connected across an impedance 21 in the receiving circuit 10 of line 6, the connection in each case being so made that the voltage from the amplifier is opposed to that in the receiving circuit due to the disturbing cause.

By this arrangement, it will be evident that effective neutralization of the interference voltages impressed on the receiving circuit of either line may be obtained by varying the magnitude of the impedance 20 or 21, or the amplification of the amplifier 18 or 19, or by varying the amount of the impedance 16 or 17 across the input circuit of the amplifier. At the same time the signaling or other currents in one of the cables will have no effect upon the receiving circuit of the other cable, because vacuum tube amplifiers are unidirectional devices and permit no energy to pass back from the line toward the common connection at the controlling circuit 13. Obviously the arrangement is applicable to any number of transmission circuits which are subject to the same disturbing influences.

Fig. 2 illustrates a similar arrangement in which the connection to the several lines to be protected is inductive instead of conductive, as in Fig. 1; also a separate transformer winding is used to supply each amplifier. The three lines 25, 26 and 27 represent a number of circuits subject to the

same disturbances. Each is connected to a receiving circuit,—28, 29, 30 respectively,—by a transformer. The transformer 31 in the circuit 25, which may be selected as the 5 neutralizing line, is provided with extra windings, 32, 33,—one for each circuit of the group to be protected—and these are connected respectively in closed circuits including similar extra windings 34, 35 on 10 the transformers 36, 37, connecting the lines 26, 27 with their respective receiving circuits 29, 30. Each of these closed circuits includes a vacuum tube amplifier—38, 39—whose functions are the same as those described 15 in connection with Fig. 1.

In Fig. 3, the connection between the correcting line 40 and the amplifiers 41 and 42 is conductive instead of inductive as in Figs. 1 and 2. To provide for such a connection 20 the impedance 43, in the line 40 is preferably so located that one of its terminals is immediately connected to ground. It is here shown as between the receiving apparatus 44 and the point 45 where the line is 25 grounded, but obviously the condition is satisfied if the impedance 43 is in parallel with the receiving apparatus. By then connecting the amplifiers in parallel as shown, the appropriate terminal of each will be 30 connected to ground. The application of the correcting voltages to the lines 46 and 47 through the impedances 48 and 49 is similar to that in Fig. 1 and requires no further explanation except to note that the 35 impedances 43, 48 and 49 should occupy corresponding positions in the several circuits. Manifestly the lines 40, 46 and 47 may represent any sort of signaling circuits whether telephone or telegraph.

40 Fig. 4 shows the application of the modification of Fig. 3 to a group of duplexed telegraph lines 50, 51 and 52. Each line is provided with the customary ratio arms 53 and 54 connected between the main line and 45 the artificial line as shown, but here the transmitting device 55, preferably in series with a condenser 56, is connected across the ratio arms between the main and artificial lines, and the receiving device 57 is connected to the apex of the ratio arms on one side and to ground on the other. By then connecting impedances 58, between the receiving apparatus and the ground in each of the lines, the interfering potentials arising 50 in the line 50 may be applied to neutralizing those in the other lines and the ground connections for the amplifiers may be provided, all in the same manner as explained in connection with Fig. 3.

60 It is obvious that the circuits 5 and 6 of Fig. 1 may be either grounded or metallic circuits, and may be arranged either for simplex or duplex transmission, without affecting in any way the application of the 65 invention here described, and the same is true of the circuits of Figs. 2, 3 and 4. To illustrate the neutralizing of interference in a plurality of circuits subject to the same disturbances, two circuits only have been shown, but the application to any number 70 of circuits is obvious, since it requires merely a duplication of the arrangements illustrated and described. The arrangement of impedances, 16, 17 in Fig. 1, may of course be varied in a number of obvious 75 ways, that shown however, or any other which provides a neutral or center point, being advantageous since it allows of a ground connection α which is usually necessary for amplifiers of the unbalanced type 80 shown in Fig. 1.

In view of the fact that there is no appreciable time lag in the action of the vacuum tube amplifiers, the arrangements herein shown will provide for the neutralization 85 not only of periodic, but also of transient interference. Where a short piece of cable grounded some distance out is used as the neutralizing conductor, as suggested in connection with Fig. 1 the cables may be 90 grounded locally, and the operation of each cable will be practically the same as if it were separately grounded a corresponding distance out.

Various modifications in the details, will 95 suggest themselves to those skilled in the art, without departing from the spirit and scope of the invention described, and the circuit arrangements here shown are therefore to be regarded as illustrative merely. 100

What I claim is:

1. In a system for neutralizing interference, a plurality of conductors subject to the same disturbing influences, circuits interconnecting said conductors and arranged 105 to oppose the disturbing potential arising in one conductor to those arising in other conductors of the group, and unidirectional devices located in said interconnecting circuits to prevent reaction between said other conductors.
2. In a system for neutralizing interference, a plurality of conductors subject to the same disturbing influences, a neutralizing conductor also subject to the same influences, 115 circuits connecting said neutralizing conductor with each of the other conductors and arranged to oppose the disturbing potential arising in the neutralizing conductor to the disturbing potential arising in each of the 120 other conductors, and unidirectional devices located in said connecting circuits to prevent reactions between said other conductors.
3. In a system for neutralizing interference, a plurality of conductors subject to 125 the same disturbing influences, a neutralizing conductor also subject to the same influences, circuits connecting said neutralizing conductor with each of the other conductors and arranged to oppose the disturb- 130

ing potential arising in the neutralizing conductor to the disturbing potential arising in each of the other conductors, and unidirectional amplifying devices located in said connecting circuits to prevent reactions between said other conductors.

4. In a system for neutralizing interference, a plurality of conductors subject to the same disturbing influences, a neutralizing conductor also subject to the same influences, circuits connecting said neutralizing conductor with each of the other conductors and arranged to oppose the disturbing potential arising in the neutralizing conductor to the disturbing potential arising in each of the other conductors, and vacuum tube ampli-

fiers located in said connecting circuits to prevent reactions between said conductors.

5. In a system for neutralizing interference, a plurality of conductors subject to the same disturbing influences, circuits interconnecting said conductors and arranged to oppose the disturbing potential arising in one conductor to those arising in other conductors of the group, and means associated with said interconnecting circuits to prevent reaction between said other conductors.

In testimony whereof I have signed my name to this specification this twenty seventh day of February, 1919.

WILLIAM H. MARTIN.
